UNITED STATES PATENT OFFICE.

CARL L. HERBERT, OF EL RENO, OKLAHOMA.

DESIGN FOR AN ADVERTISING BOARD.

61,341.

Specification for Design.

Patented Aug. 8, 1922.

Application filed November 5, 1921. Serial No. 513,187. Term of patent 3½ years.

To all whom it may concern:

Be it known that I, CARL L. HERBERT, a citizen of the United States, residing at El Reno, in the county of Canadian and State of Oklahoma, have invented a new, original, and ornamental Design for an Advertising Board, of which the following is a specification, reference being had to the accompanying drawing, forming part thereof.

The figure is a perspective view of an advertising board embodying my design.

I claim:

The ornamental design for an advertising board, as shown.

CARL L. HERBERT.
